UNITED STATES PATENT OFFICE.

CONRAD DIESEL, OF CHICAGO, ILLINOIS.

DESIGN FOR A SHEET-METAL CAN.

SPECIFICATION forming part of Design No. 29,180, dated August 9, 1898.

Application filed December 27, 1897. Serial No. 683,773. Term of patent 14 years.

To all whom it may concern:

Be it known that I, CONRAD DIESEL, a citizen of the United States, residing at Chicago, in the county of Cook and State of Illinois, have invented and produced a new and original Design for a Sheet-Metal Can, of which the following is a specification, reference being had to the accompanying drawings, which are made a part hereof, and in which—

10 Figure 1 is a perspective view of a can embodying the new design. Fig. 2 is a vertical section thereof on the line 2 2, Fig. 1.

The subject of the present invention is a design for an unclosed sheet-metal can, and a 15 can embodying all features of the new design, both essential and minor, is shown in the drawings. It has a cylindrical body A, provided at top with a marginal bead a. At a short distance below this bead the body has a 20 rib a', and that portion of the body which is above this rib is surrounded by a raised band B, which projects some distance above the top of the body proper and forms an upward extension, as to which the bead a forms an internal shoulder. The surface of the band 25 has a circumferential mark b, dividing it into two circumferential divisions b' and b''. The continuity of the division b' is broken by a tongue B', and the outer surfaces of the tongue

and band at the point where they join are 30 flush. The continuity of the division b'' is broken by a transverse line b², (the end of the strip of which the band is formed,) which in the vicinity of the tongue B' is deflected, forming an angular notch b³ opposite the 35 mark b.

The essential and leading features of the design are the cylindrical body A, surrounded by the band B, having the two divisions b' and b'' separated by the mark b, the tongue B', the 40 outer surface of which is flush with the outer surface of the band at the point where they join, said tongue breaking the continuity of the division b' and line b² breaking the continuity of the division b'' and deflected to form 45 the notch b³ opposite the mark b. Minor features of the design are the internal bead a and the rib a' when accompanied by the other features above enumerated.

What I claim as new, and desire to secure 50 by Letters Patent, is—

The design for a sheet-metal can, substantially as herein shown and described.

CONRAD DIESEL.
